UNITED STATES PATENT OFFICE

97,440

DESIGN FOR A TEXTILE FABRIC

Julia Morris, New York, N. Y., assignor to Phoenix
Manufacturing Company, Inc., New York, N. Y., a corporation of New York

Application September 27, 1935, Serial No. 58,860

Term of patent 3½ years

To all whom it may concern:

Be it known that I, Julia Morris, a citizen of the United States, residing in the Borough of Manhattan, city, county, and State of New York, have invented a new, original, and ornamental Design for a Textile Fabric, of which the following is a specification, reference being had to the accompanying drawing, forming part thereof.

In the drawing the figure shows a plan view of a piece of textile fabric embodying the design of the present invention.

I claim:

The ornamental design for textile fabric, as shown.

JULIA MORRIS.
